UNITED STATES PATENT OFFICE.

W. S. COLWELL, OF ALLEGHENY CITY, PENNSYLVANIA.

IMPROVEMENT IN PLOWS.

Specification forming part of Letters Patent No. 88,851, dated April 13, 1869.

To all whom it may concern:

Be it known that I, WILLIAM S. COLWELL, of the city and county of Allegheny, in the State of Pennsylvania, have invented a new and useful Improvement in Plows; and I do hereby declare that the following is a full, clear, and exact description thereof, reference being had to the accompanying drawings, and to the letters of reference marked thereon.

The nature of my invention consists in providing plows with a mold-board, the surface of which is convexed and curved from its point to its heel, and the transverse plause of its surface being straight and convexed, in the manner and for the purpose hereinafter described.

To enable others skilled in the art to make and use my invention, I will proceed to describe its construction and operation.

In the accompanying drawings, which form part of my specification, Figure 1 is a side elevation of a plow provided with my improvement in mold-boards. Fig. 2 is a top view or plan of the same. Fig. 3 is a transverse section of the same when cut through at line y of Fig. 1. Fig. 4, Sheet B, represents a perspective view of a block of wood for making the pattern of my improvement in plows, representing the manner of laying out the lines for obtaining the desired contour of the mold-board and landside. Fig. 5, Sheet B, is an inverted view, in perspective, of said block of wood.

To make a medium-sized plow—say about ten inches wide at the base, and from the point of the mold-board to its heel about thirty-two inches, and from the outer face of the landside to the outer line of the top edge of the mold-board at its heel about seventeen inches wide—I take a block of the form represented in Figs. 4 and 5, measuring in length about thirty-two inches, thirteen inches deep, and seventeen inches wide. Now, taking the surface A' of the block for the outer face of the landside, I make a gage-mark, C' and D', about ten inches from the face A'. The line D' will give the width of the plow at its base, and the line C' will enable me to obtain the desired longitudinal convexity by placing a mark at o', and marks at o² and o³, and then striking a line which will form the arc of a circle, said line passing over the marks o', o², and o³. I then strike a curved line, e', from point o² to point o⁴. This will give

the desired curve for the front edge of the standard of the plow. The curve e' may form an arc of any size of a circle, so that said curve e' may be made to suit the taste of the plow-maker. I then draw a line, f', from point o³ to point o⁵, where line 5 joins D'. This will give the desired curve or twist longitudinally and transversely of the mold-board—that is to say, the desired angle for turning over the furrow. Having the lines laid out as described, and as represented in Figs. 4 and 5, I then cut away that portion of the block marked s to the lines h', f', and e'. I then mark out the furrow-line f, (see Figs. 1 and 3,) which must measure about ten inches from the base-line, (see Fig. 2,) following the vertical and transverse angle of the mold-board. I then make a vertical line, i', from point o' to a point midway on line D'. I then make marks on the furrow-line about two and one-half inches apart, commencing at line i', marking fore and aft on said furrow-line. I then draw straight lines between these marks and then draw the lines Z, which are at right angles to said straight lines, and with suitable tools dress off the face of the mold-board until a straight-edge touching or resting on lines h' and D', will also touch at all points on the lines Z on the face of the mold-board, which will give the desired form of mold-board, with curves, convexities, and angles, hereinbefore described.

The share-bed in the mold-board is made in the ordinary manner. The timber between the landside and mold-board is cut out, so as to give the desired thickness of the landside and mold-board. The contour of the upper edge and back end of the mold-board and landside may be made to suit the taste of the plow-maker.

In the drawings, C represents the mold-board. e represents the plow-share. D represents the landside, and h the standard to which the beam of the plow is attached:

The surface of the mold-board from its point A to its heel B is convexed, and on the lines Z the surface is straight—that is to say, by placing a straight-edge on the lines Z the surface of the mold-board will be found to be parallel with the straight-edge. This straight surface is clearly shown at line o in Fig. 3; but if the straight-edge is placed on the lines X the surface will be found to be convexed. The

mold-board is also curved or twisted from its point A to its heel B, as shown clearly in Fig. 2, and the outer line or edge, *i*, of the base of the mold-board is parallel with the longitudinal plane of the landside D, as shown in Fig. 3. The mold-board and landside are braced by the cross-piece *l*.

The line *f* represents the top line of the furrow when resting on or against the mold-board.

With exception of the mold-board, in all other respects the plow and its parts are constructed in the usual manner.

By making the mold-board in the manner and form herein described and represented the plow will be easily controlled by the plowman, and the plow will have a very light draft.

Having thus described the nature, construction, and operation of my improvement, what I claim as of my invention is—

Providing a plow with a mold-board the surface of which is from its point A to its heel B convexed, and also convexed on the lines X and straight on the lines Z, and curved from point A to heel B, as herein described, and for the purpose set forth.

W. S. COLWELL.
